DEVICE FOR EMPTYING CONTAINERS

Arno Demmler, Reichenbach in Vogtland, and
 Walter Greppert, Brandenburg, Germany, as
 signors to Otto Billian, Zurich, Switzerland

Application June 12, 1934, Serial No. 730,228
 In Germany June 13, 1933

7 Claims. (Cl. 221—23)

Our invention relates to a device for emptying containers, such as tins, jars, or the like, for milk, oil, fruit juice, or any other liquid.

It is an object of our invention to provide a device of the type referred to in which dripping, soiling of tables and other articles, and the formation of liquid residues on the containers themselves, are eliminated. Residues are particularly undesirable because they attract flies and other insects which contaminate them.

With the object of our invention in mind, we provide a bracket which is adapted to be placed on a container, for instance, by means of lugs at opposite ends of the bracket, and on this bracket we provide an outflow pipe, with means such as a punch which is mounted to slide in the pipe, for forming a liquid-outlet hole in the container so that the liquid, when the punch is retracted and lays open outlet hole, flows out through the hole and the pipe. We further provide, also on the bracket, means such as a screw with a pointed and slotted end, which screw is inserted in a threaded hole of one of the lugs and serves for holding the bracket on the container and for forming an air-inlet hole in the container. Air is drawn into the container through the air-inlet hole as the liquid flows out, the slotted end of the screw serving as the air duct. The admission of air is cut off by screwing in the screw until the outer end of the slot is within the container.

In the accompanying drawings, devices embodying our invention are illustrated by way of example.

In the drawings:

Fig. 1 is a partly sectional elevation of a device with an undivided bracket,

Fig. 2 is a section on the line II—II in Fig. 1, drawn to a larger scale,

Fig. 3 is a plan view of Fig. 1,

Fig. 4 is a partly sectional elevation of a divided bracket,

Fig. 5 is a sectional elevation of a movable lug on the bracket, in which lug the screw for forming the air-inlet hole is inserted,

Fig. 6 is a partly sectional elevation showing a lug as in Fig. 5, equipped with a handle,

Fig. 7 is a modification of the lug and handle illustrated in Fig. 6, in which the handle is made of elastic material,

Fig. 8 is an elevation of a device with a handle at one end of its undivided bracket, showing the device in position on a container which is partly broken open,

Fig. 9 is a partly sectional elevation of a device

whose outflow pipe has a spring catch for the punch,

Fig. 10 is a partly sectional elevation of a device with an elongated handle on its pointed screw,

Fig. 11 is a partly sectional elevation of a device whose outflow pipe is secured to a lug on the bracket, and not arranged on top of the bracket, as in the other modifications which have been illustrated.

Referring now to the drawings, and first to the device illustrated in Figs. 1, 2, and 3, the bracket 1 of this device is undivided and is equipped with a lug 2 at one of its ends, and with a lug 3 at the other end, so that the bracket resembles the letter "U", inverted. In this position, the bracket 1 is placed on a container, here shown as a tin 4, so that the lug 2 at the left engages the side of the tin, or rather the downturned flange at the top of its lid 12. The inner face of lug 2 is preferably curved to a radius substantially equal to the radius of the tin 4, to give the lug a better seat on the flange of the lid.

The other lug 3 is preferably straight, as it is spaced apart from the lug 2 for such a distance that it does not engage the flange of the tin when the lug 2 has been applied to the flange.

A screw 5 is inserted in a threaded hole of the other lug 3. The inner end of the screw 5 is pointed at 6 for piercing the wall of the tin 4 and has a slot or groove 7 for admitting air to the interior of the tin through the pointed end.

The screw 5, consequently, has three functions: Firstly, it holds the bracket on the tin, secondly, it forms the air-inlet hole in the side of the tin, and thirdly it supplies the interior of the tin with air through the air-inlet hole.

An outflow pipe 9 for the liquid, with a branch pipe 10 at one side of the main pipe, is inserted in the bracket 1 so that its lower end projects from the lower face of the bracket, and a sealing ring 11, of rubber or the like, is placed on the projecting lower end of the outflow pipe 9 between the bracket 1 and the lid 12 of the tin 4.

A punch 13 is mounted to slide in the outflow pipe 9 with a cylindrical collar 14. A recess is formed by the upper face of collar 14 and the lower face of a collar 15 which is only partly cylindrical, or crescent-shaped, as best seen in Fig. 2. The two collars are connected by a push rod 16, and a check 17, here shown as a screw with a slotted end, is inserted in the wall of pipe 9 so as to engage in the recess between the two collars 14 and 15 when the collar 15 is in the position of

Fig. 1. A spring 18 is placed on the rod 16, with its lower end bearing on the collar 15, and its upper end supported by a cap 99 at the upper end of pipe 9. The upper end of rod 16 projects from the upper end of pipe 9 and is equipped with a handle or knob 19 for shifting and turning the rod.

In operation, the bracket 1 is placed on the tin 4 as shown, and the handle 8 at the outer end of the screw is turned so as to drive its inner or pointed end 6 into the side wall of the tin 4. When the side wall has been pierced by the point 6, air is admitted to the container through slot 7.

The handle or knob 19 on the push rod 16 is now turned until the collar 15 clears the check 17, and the rod is depressed until the punch 13 has pierced the lid 12 of the tin 4 to form the liquid-outlet hole therein. The spring 18 holds the punch in the hole it has formed. When it is desired to empty the container, or to tap a portion of the liquid from it, the rod 16 is raised until the collar 15 is above the check 17, in which position, as shown in Fig. 1, the collar 14 of the punch 13 exposes the inner opening of the branch pipe 10, and the rod is then turned so that the collar 15 is suspended on the check 17. When the tin is inverted, liquid flows out through the punched outlet hole in the lid, and the pipes 9, 10, while air is admitted through the slot 7 of screw 5.

If only a portion of the liquid is to be tapped, the rod 16 is again turned until the collar 15 clears the check 17, whereupon the spring 18 returns the punch 13 to the position in which it closes the hole it has made. The screw 5 is now turned inwardly until the outer end of its slot 7 is within the container and the access of atmospheric air to the container is interrupted. When it is desired to tap more liquid from the tin, or to empty it, the screw 5 is withdrawn until its slot 7 admits atmospheric air, and the rod 16 is raised and suspended by its collar 15 as described.

It will be understood that the operation of our device for emptying or tapping containers is clean and without waste, and that no residues of liquid are left on the tin after tapping or emptying.

In order to adapt the bracket to tins or other containers of substantially different diameters, the means illustrated in Figs. 4 to 7 may be used.

Referring first to Fig. 4, the bracket is subdivided into a part 20, with the outflow pipe 9, and the lug 2', and a part 21, with the lug 3'. The part 21 has equidistant threaded holes 22 and the part 20 has a locating member 23 which engages in one of the holes 22, according to the relative position of the parts 20 and 21. A screw 24, with a handle 25, is inserted in one of the threaded holes 22 through a plain hole in the part 20 for connecting the two parts. In order to vary the span of the lugs 2' and 3', the screw 24 is unscrewed from the hole 22 in which it had been, the parts are shifted as required, and the screw is re-inserted.

The lug in which the screw 5 is mounted, may be an independent member, and mounted to be displaced on the bracket 1'. Such a lug is shown in Fig. 5, where the lug 26 has a hole for sliding on the plain end of bracket 1'. The other end of the bracket has the lug 2', as described. Edges 27 and 28 are formed in the hole of the lug 26 for engaging the upper and lower faces of the bracket 1', and fixing the lug on the bracket, when the screw 5 is set.

Referring to Fig. 6, the lug 26' is equipped with a handle 29 which has the shape of an inverted "L", with a short horizontal upper por-

tion, and a longer vertical lower portion. Where the two portions merge into each other, the handle has a hole 30 for the free passage of a bracket whose end is plain here, while the other end has a lug similar to the lug 2.

The handle may be elastic, as shown in Fig. 7. Here, the lug 26'' has only the lower edge 28', and another edge 31 is formed in the hole 30', for engaging the bracket from below. The reaction of the elastic handle 29' forces the edges 28' and 31 against the face of the bracket from below, holding the lug 26'' on the bracket.

Referring now to Fig. 8, the lug 3'' at the right of the bracket 1'' is elongated in downward direction, and equipped with a handle 32. When the screw 5' has been driven home the bracket 1'' and the tin 4' are rigidly connected and the handle 32 serves for manipulating the tin, for instance, for placing it on a stand 33. Obviously, such a handle may also be provided on the divided bracket illustrated in Fig. 4.

The outflow pipe 9' and its branch pipe 10' may be cast as a single member, as shown in Fig. 8, with a rib 34 connecting the two pipes.

A cast member facilitates the provision of a spring catch for the push rod 16', as shown in Fig. 9. A ball 35 is inserted in a bore 36 of the member and urged into grooves 37 and 38 of the rod by a spring 39 in the bore 36.

The screw 5' may be equipped with a flange 40 and a sealing washer 41 at its pointed end, as shown in Figs. 8 and 9. Obviously, the outer end of slot 7' must extend beyond the outer face of flange 40, as shown in Fig. 9.

Fig. 10 shows a long handle 42 on the screw 5'' which performs the same function as the handle 32 in Fig. 8, and in addition serves for pushing home the screw 5'' by rotation of the handle 42.

As shown in Fig. 11, an outflow pipe 43 may be inserted in the lug 2'' and equipped with the sealing ring 11', like the outflow pipe. The outer end of the pipe 43 has a female thread 44 to be engaged by a male thread 45 on the rod 16'', for piercing the side wall of the tin with the point or punch 13' at the inner end of the rod.

It is understood that the pipe 43 may be arranged on any bracket, and not only on a bracket of the type shown in Fig. 5, as illustrated by way of example in Fig. 11.

We claim:

1. In a device for emptying containers, a bracket adapted to be placed on a container, an outflow pipe on said bracket, a punch mounted to slide in said outflow pipe for punching a liquid-inlet hole in the container, means for holding said punch in the liquid-inlet hole, means for keeping said punch in a position, against the action of said holding means, in which it exposes the liquid-outlet hole, and means on said bracket for holding the bracket on the container and for forming an air-inlet hole in the container.

2. In a device for emptying containers, a bracket adapted to be placed on a container, an outflow pipe on said bracket, a punch mounted to slide in said outflow pipe for punching a liquid-outlet hole in the container, means for holding said punch in the liquid-outlet hole, means for keeping said punch in a position, against the action of said holding means, in which it exposes the liquid-outlet hole, a branch pipe connected to said outflow pipe at a point beyond which said punch is moved by the operation of

said keeping means, and means on said bracket for holding the bracket on the container and for forming an air-inlet hole in the container.

3. In a device for emptying containers, a bracket adapted to be placed on a container, an outflow pipe on said bracket, a punch mounted to slide and to turn in said outflow pipe for punching a liquid-outlet hole in the container, means for holding said punch in the liquid-outlet hole, a collar on said punch which is partly cut away, and a check on said outflow pipe adapted to cooperate with said collar: for keeping said punch in a position, against the action of said holding means, in which it exposes the liquid-outlet hole, means for turning said punch to disengage its collar from the check, and means on said bracket for holding the bracket on the container and for forming an air-inlet hole in the container.

4. In a device for emptying containers, a bracket adapted to be placed on a container, an outflow pipe on said bracket, a punch mounted to slide and to turn in said outflow pipe for punching a liquid-outlet hole in the container, a spring for holding said punch in the liquid-outlet hole, a collar on said punch which is partly cut away, and a check on said outflow pipe adapted to cooperate with said collar: for keeping said punch in a position, against the action of said spring, in which it exposes the liquid-outlet hole, means for turning said punch to disengage its collar from the check, and means on said bracket for holding the bracket on the container and for forming an air-inlet hole in the container.

5. In a device for emptying containers, a bracket adapted to be placed on a container, a fixed lug at one end of said bracket, a movable lug having an opening with which it is mounted to slide on the other end of said bracket, an edge in said

opening adapted to engage said bracket, an outflow pipe on said bracket, means in said outflow pipe for forming a liquid-outlet hole in the container, and means on said movable lug for: holding the bracket on the container, fixing the movable lug on the bracket by causing said edge to bite into the bracket, and forming an air-inlet hole in the container.

6. In a device for emptying containers, a bracket adapted to be placed on a container, a fixed lug at one end of said bracket, a movable lug having an opening with which it is mounted to slide on the other end of said bracket, an edge in said opening adapted to engage said bracket, an elastic handle on said movable lug having an opening with which it is mounted to slide on the other end of the bracket together with the movable lug, an edge in the opening of said handle also adapted to engage said bracket, said movable lug and said handle being so arranged with respect to each other that the reaction of the handle causes the two edges to bite into the bracket, an outflow pipe on said bracket, means in said outflow pipe for forming a liquid-outlet hole in the container, and means on said movable lug for holding the bracket on the container and for forming an air-inlet hole in the container.

7. In a device for emptying containers, a bracket adapted to be placed on a container, an outflow pipe on said bracket, means in said outflow pipe for forming a liquid-outlet hole in the container, a spring catch in said pipe for holding said means in two distinct positions, and means on said bracket for holding the bracket on the container and for forming an air-inlet hole in the container.

ARNO DEMMLER.
WALTER GREPPERT.
